CLAIM

I claim the ornamental design for electrical / datacomm scissors, as shown and described.

DESCRIPTION

FIG. 1 is a perspective view of one embodiment of electrical / datacomm scissors showing the new design;

FIG. 2 is a left side elevational view thereof;

FIG. 3 is a right side elevational view thereof;

FIG. 4 is a bottom view thereof;

FIG. 5 is a top view thereof;

FIG. 6 is a rear elevational view thereof;

FIG. 7 is a front elevational view thereof;

FIG. 8 is a perspective view of an alternative embodiment of electrical / datacomm scissors;

FIG. 9 is a left side elevational view thereof;

FIG. 10 is a right side elevational view thereof;

FIG. 11 is a bottom view thereof;

FIG. 12 is a top view thereof;

FIG. 13 is a rear elevational view thereof; and,

FIG. 14 is a front elevational view thereof.
